UNITED STATES PATENT OFFICE.

CHARLES W. HOWELL, OF NEWARK, NEW JERSEY, ASSIGNOR TO SUN TYPE-WRITER COMPANY, OF NEWARK, NEW JERSEY, A CORPORATION OF NEW JERSEY.

TYPE-WRITING MACHINE.

No. 852,721.

Specification of Letters Patent.

Patented May 7, 1907.

Application filed January 28, 1905. Serial No. 243,077.

To all whom it may concern:

Be it known that I, CHARLES W. HOWELL, a citizen of the United States, and a resident of Newark, in the county of Essex and State 5 of New Jersey, have invented new and useful Improvements in Type-Writing Machines, of which the following is a specification.

This invention relates to writing machines of the front strike variety, in which the type-bars carry multiple types, provision being made for shifting the platen up and down to enable different types to print. In the particular class of machines to which my invention pertains, the carriage travels upon tracks 10 which are mounted upon a frame, the latter being shiftable up and down together with the carriage and platen.

The object of my invention is to improve and simplify the shifting mechanism particularly with a view to economy in manufacture, durability, ease and certainty of operation, compactness of parts, and lightness of structure.

My invention further relates to improvements in the key mechanism for shifting the platen to different points from normal position.

To these and other ends, my invention consists in certain combinations of devices, 30 construction of mechanism, and arrangements of parts, all as will be hereinafter set forth, and particularly pointed out in the concluding claims.

In the accompanying drawings: Figure 1 is a sectional elevation taken from front to rear of a "Sun" typewriting machine, showing my improvements applied thereto. Fig. 2 is a front elevation of the shift-key mechanism. Fig. 3 is a side elevation of the machine, showing the platen and carriage shifted to position for writing figures. Fig. 4 is a view similar to Fig. 2, but showing the figure key as having been depressed as seen at Fig. 3. Fig. 5 is a plan of the frame-work of the machine, the shiftable carriage-track frame, and shift key mechanism, with connections. Fig. 6 is a rear view of the carriage-track frame and connections.

The framework of the machine comprises 50 a rectangular base having sides 1, 2, front wall 3, and rear wall 4. Type-bars 5, which swing rearwardly against a platen 6, are pivoted upon a rod 7 mounted in a fixed segment 8. The type-bars are connected by

links 9 to bell-cranks or levers 10, bearing 55 character-keys 11. The platen 6 is journaled in the sides or ends 12, 13 of a carriage; which also comprises a rear bar 14, and runs upon tracks 15 and 16, the former being grooved to receive bearing balls 17, and the 60 carriage-frame comprising a longitudinal bar 18, which is grooved on its under side to match the track 15, so that the carriage is guided by the balls 17. The rear bar 14 of the platen frame is formed with a flange 19, 65 which rests upon the track 16 and is retained by keepers 20. The balls 17 are directly under the platen, and sustain the principal portion of the weight of the carriage, so that the latter runs freely and accurately. The carriage frame also comprises a rack-bar 21, engaging a pinion 22, the latter connected to an escapement wheel 23, which in turn is controlled by the type-keys by means of suitable mechanism (not shown). The pinion 22 is 70 long enough to maintain engagement with the rack 21 as the latter shifts up and down with the carriage, the axis of said pinion being vertical, to correspond with the shifting movement of the carriage. The carriage is 75 propelled by a spring barrel 24, being connected thereto by a strap 25.

The tracks 15 and 16 are carried upon or form a part of a vertically shiftable frame, the principal portions of which form a single 85 casting, and comprise upper and lower bars 26 and 27, and sides or ends 28, arms 30 extending forwardly from said sides to support said track 15. The carriage-track frame or casting also comprises a yoke 31, which is connected to the ends of the frame and carries a depending arm 32, the lower end of which is pivoted at 33 to the rear end of a member generally designated as 34, which serves as a guide-link for said arm, and is in the form of 90 a vibrating frame, movable up and down upon pivots 35 fixed in the opposite sides of the base; said frame 34 comprising a rear bar 36, a shaft 37, and braces 38, all forming a single casting; said shaft being supported at 95 its ends upon said pivots 35, and carrying an adjustable spring 39, which partly balances the weight of the platen carriage and carriage-track frame.

To the sides of the carriage-track frame 105 are pivoted at 40, the rear ends of a pair of links 41, which extend downwardly from said pivots and forwardly beneath the track 15.

and are pivoted at their front ends at 42 to standards 43 cast upon base sides 1 and 2, and forming part of the frame-work of the machine. These links 41 guide the carriage track frame vertically, that is, they prevent said frame from moving backward or forward to any appreciable extent during the shifting movements of said frame; while the member 34 in the base serves as a link to 10 guide the lower end of the carriage-track frame; so that the latter must move up and down in a substantially vertical path, determined by the co-operation of links or link members 41 and 34.

15 Normally the carriage-track frame rests upon an adjustable stop-screw 44, said frame being provided with a lug 45 for this purpose; and the upward movement of the frame is limited by an adjustable stop-screw 46, 20 which is in the path of a part 47 cast upon the frame.

In order to maintain the carriage tracks level, I prefer to use a pair of rods, props or supports 48 between the sides 28 of the carriage track frame and the sides of the vibrating frame which lies across the base and comprises the parts 36, 37 and 38. The pointed tops of said rods are inserted in holes or cups 49 formed in the sides 28; and the rods are 25 also pointed at their bottom ends and inserted in the cupped tips of adjustable screws 50, which extend up through arms 51^a cast upon the said vibrating frame and connected by the bar 36. By adjusting the screws 50 independently up and down, the rods 48 may 30 be caused to support the carriage-track frame equally, so that the level of the latter is maintained under all conditions, while freedom of movement of the parts is permitted, 35 since said rods fit loosely in the holes or cups formed in the carriage-track frame and the screws 50.

In order to prevent lateral or transverse movement of the carriage-track frame, that 40 is, movement in direction of the run of the carriage, I fix a bracket or transverse bar 54 upon the base, upon which I cast vertical guides 52 and 53, having upon their opposing faces vertical ball grooves 54, in which run 45 balls 55; while upon the carriage-track frame I provide a pair of flanges 56, between said guides 52, 53, to co-operate with said grooves 54 to form raceways for the balls; the working faces of said flanges being vertical and 50 plane. The only function of this guiding means is to prevent movement of the carriage-track frame transversely of the machine during its up and down movements, and grooves are hence unnecessary in said 55 flanges. This plane construction of the bearings 56 permits the carriage-track frame to move up and down in an arc about the pivots 42, notwithstanding the guiding of the balls 55 in the vertical guides 54. Thus it will be 60 seen that the carriage-track frame cannot

bind under any circumstances, but must always move freely and accurately; while the parts are simple in construction and operation. The guides 54 may be provided with 65 keepers 57 for the balls.

70 From the shaft 37 of the horizontal shifting frame in the base extends forward an operating arm 58, carrying a capital shift-key 59 and a figure-shift key 60. When the parts are in normal position, as at Fig. 1 and 2, the 75 platen is at its lowest point, so that when the type-bars are operated the lower case letters print. By depression of the operating arm 58, the carriage-track frame is lifted to a position to enable the capital types to print, 80 these being the middle types upon the type-bars; the upward movement of the carriage-track frame being limited by the engagement of a stop 61 with a lug 62 fixed upon the base of the machine. Said stop 61 may be 85 moved out of the way of the lug 62, so as to permit a full upward movement of the carriage-track frame and platen to the position seen at Fig. 3, to enable the figures to print; such movement of the stop 61 being provided 90 for by pivoting the stop at 63, upon the front end of the operating arm 58; the figure key 60 being secured upon the same pivoted plate 64 that carries said stop 61, and said figure key being upon the right of said pivot 63, 95 while said stop is below said pivot, so that when said key is depressed, it causes the stop 61 to swing to the left, where it will not encounter the lug 62. The key 59 may be also secured upon the same plate 64, and the vibration of the plate may be limited by a lug 65 projecting forward from the tip of the operating arm 58, within a notch 66 formed upon said plate 64. By having the key 59 at the left and the key 60 at the right of pivot 63, it is insured that the stop 61 shall be rendered either active or inactive according to the key depressed, the pressure upon either of said keys causing a movement of said stop in either one direction or the other, to an extent governed by the lug 65.

110 A locking lever 67 is pivoted at 68 to the base of the machine, and provided with a friction spring 69 and a finger piece 70. The operating arm 58 has upper and lower bearing surfaces 71 and 72, upon which catches a hook 73 of said locking lever; the engagement of the latter with the bearing 72 serving to lock the carriage-track frame in capital-shift position, and its engagement with the bearing 71 serving to lock the carriage-track frame in figure-shift position. The bearings or surfaces 71 and 72 are nearly concentric with the pivot 68, so that after depression of either key 59 or 60, it is only necessary to 120 push back the finger piece 70 in order to lock the carriage.

Variations may be resorted to within the scope of my invention, and portions of my improvements may be used without others. 130

Having thus described my invention, I claim:

1. In a front-strike writing-machine, the combination with a paper carriage, of a vertically shifting track-frame upon which said carriage runs, links pivoted to said frame at different heights, and also to the frame-work of the machine, and guiding means, including a set of balls, to prevent lateral movement of the shifting frame.

2. In a front-strike writing-machine, the combination with a platen carriage, of a vertically shifting frame supporting said platen carriage, horizontal links pivoted to the said frame at different heights, and means, including a set of balls, to prevent lateral play of said frame.

3. In a front-strike writing-machine, the combination with a traveling paper carriage, of a vertically shifting frame provided with front and rear guide-rails or tracks for the carriage, a vibrating horizontal frame carrying the shifting frame at its lower end, and a pair of adjustable supporting rods extending between the two frames at the sides thereof.

4. In a front-strike writing-machine, the combination with a traveling paper carriage, of a vertically shifting frame provided with front and rear guide rails for the carriage, guide links pivoted at their front ends to the framing of the machine forward of the front guide rail, and at their rear ends to the shifting frame behind the front guide rail, said links being offset to clear the guide rail, and means co-operating with said links to guide said shifting frame.

5. In a front-strike writing-machine, the combination with a paper carriage, of a vertically shifting carriage-track frame, said frame being supported at its lower end by a horizontally disposed vibrating frame to which it is pivoted, and at its upper end by pivoted links at its sides, the horizontally disposed frame and links being pivoted at their rear ends to the vertically shifting frame, and at their front ends to the frame of the machine.

6. In a front-strike writing-machine, the combination with a paper carriage, of a vertically shifting carriage-track frame, vibrating supports for the frame, consisting of links pivoted at their rear ends to the upper part of the frame, and a horizontal frame pivoted at its rear end to the lower part of the shifting frame, said horizontal frame being pivoted to the base of the machine, and being provided with a forward extension having a shift-key.

7. In a front-strike writing machine, the combination with a base, of a horizontal frame lying across said base and journaled thereon, so that the rear part of said frame may vibrate up and down, a key connected to said frame, a carriage-track frame movable up and down and having a depending

arm pivoted to the rear portion of said vibrating frame, a platen carriage mounted upon said carriage-track frame, and rearwardly striking type-bars.

8. In a front-strike writing-machine, the combination with a base, of a horizontal frame lying across said base and journaled thereon, so that the rear part of said frame may vibrate up and down, a shift key, a carriage-track frame movable up and down and having a depending arm pivoted to the rear portion of said vibrating frame, a partial counterbalance spring for said carriage-track frame, a carriage mounted upon said carriage-track frame, and type-bars mounted to strike rearwardly.

9. In a typewriting machine, the combination with a base, of a vibrating member journaled upon said base and having a key-bearing arm extending forwardly from its journal, and also having a part extending rearwardly from said journal, a carriage-track frame having a depending arm pivoted to said rearwardly extending part, cooperative means for guiding said carriage-track frame in its upward and downward movements, a platen carriage mounted upon said carriage-track frame, and rearwardly striking type-bars.

10. In a type-writing machine, the combination with a key-controlled rocking member, of a carriage-track frame having a depending arm engaging said rocking member and guided thereby, a pair of guide-links connecting the ends of said carriage-track frame to the framework of the machine, a platen carriage upon said carriage-track frame, and rearwardly striking type-bars.

11. In a type-writing machine, the combination with a base, of a key-operated member pivoted upon said base so as to vibrate up and down, a carriage-track frame having a depending arm pivoted to the rear end of said pivoted member, a pair of guide links connecting said carriage-track frame to the framework of the machine, means, including bearing balls and tracks therefor, for guiding the carriage-track frame in its up and down movements so as to prevent lateral movement of said carriage-track frame, and rearwardly striking type-bars.

12. In a front-strike writing-machine, the combination with a base, of a member journaled in said base to vibrate up and down, a key mounted upon said member, a carriage-track frame having a depending arm pivoted to said member, a pair of links extending forwardly from the sides of said carriage-track frame and pivoting at their forward ends to the framework of the machine, a vertical fixed guide to prevent lateral movement of the carriage-track frame, a platen carriage upon said carriage-track frame, and rearwardly striking type-bars.

13. In a front-strike writing-machine, the

combination with a base, of a member pivoted thereon to vibrate up and down, a key for operating said member, a carriage-track frame having an arm pivoted to said pivoted member, fixed vertical guides extending upwardly from said base, balls in said guides, bearings upon said carriage-track frame to engage said balls, whereby the carriage-track frame is prevented from moving laterally, and links extending forwardly and pivoted at their front ends upon the framework.

14. In a front-strike writing-machine, the combination with a base, of a member pivoted upon the base, a shift-key, a carriage-track frame pivoted to said member, upwardly extending vertical guides fixed upon said base, balls in said guides, bearings upon said carriage-track frame to engage said balls, whereby the carriage-track frame is prevented from moving laterally, links extending forwardly to the front of the machine and pivoted at their front ends upon the framework, a driving spring mounted upon said carriage-track frame and connected to the carriage, an escapement wheel mounted upon the framework of the machine, and means connecting said escapement wheel to the carriage at all shift positions of the latter.

15. In a front-strike writing machine, the combination with a base, of a frame lying horizontally within said base and extending across the same and journaled thereon, a carriage-track frame having an arm pendent from the middle portion thereof and pivoted to said journaled frame, supports extending up from the sides of said journaled frame to the sides of said carriage-track frame, means for guiding the carriage-track frame up and down, a platen carriage upon said carriage-track frame, and rearwardly striking type-bars.

16. In a front-strike writing machine, the combination with a base, of a key-operated frame lying horizontally within said base and extending across the same and journaled thereon, a carriage-track frame having a pendent arm pivoted to the middle portion of said key-operated frame, vertically adjustable links or supports extending up from the sides of said key-operated frame to the sides of said carriage-track frame, a pair of guide-links extending forwardly from said carriage-track frame and pivoted to the framework, fixed vertical guides for said carriage-track frame, a platen carriage upon said carriage-track frame, and rearwardly striking type-bars.

17. In a front-strike writing machine, the combination with a platen-carriage and series of rearwardly striking type-bars, of a vertically shiftable carriage-track frame whereon said carriage runs, a pair of links pivoted to the sides of said carriage-track frame and extending forwardly and connected at their forward ends to the framework,

and means co-operating with said links to guide said carriage-track frame in its up and down movements.

18. In a front-strike writing-machine, the combination with a platen carriage and a series of rearwardly striking type-bars, of a vertically shiftable carriage-track frame whereon said carriage runs, a pair of links pivoted to the sides of said carriage-track frame and extending forwardly and connected at their forward ends to part of the framework, and means co-operating with said links to guide said carriage-track frame in the up and down movements; said guiding means including an arm depending from said frame, and a guiding member pivoted to the lower end of said arm and also pivoted to the framework.

19. In a front-strike writing-machine, the combination with a platen carriage and a series of rearwardly striking type-bars, of a carriage-track frame whereon said carriage runs, said frame being movable up and down, a pair of links pivoted to the sides of said carriage-track frame and extending forwardly and connected at their forward ends to part of the framework, and means co-operating with said links to guide said carriage-track frame in its up and down movements; said guiding means including an arm depending from said carriage-track frame, a device guiding the lower end of said arm, and vertical guiding means which prevent lateral movement of said carriage-track frame; said vertical guiding means including vertical grooves, balls in said grooves, and bearings for said balls.

20. In a front-strike writing-machine, the combination with a platen carriage and a series of rearwardly striking type-bars, of a track frame whereon said carriage runs, said frame being vertically movable, a pair of links pivoted to the sides of said carriage-track frame and connected at their ends to a part of the framework, and means co-operating with said links to guide said carriage-track frame in its up and down movements; said guiding means including an arm depending from said frame, a device guiding the lower end of said arm and also including a member having a pair of vertical ball grooves and a member having bearing surfaces opposed to said grooves, and balls in said grooves.

21. In a front-strike writing-machine, the combination with a carriage and a series of rearwardly striking type-bars, of a vertically movable carriage-track frame whereon said carriage runs, a pair of horizontal links pivoted to the sides of said carriage-track frame and extending to a part of the framework, and means co-operating with said links to guide said carriage-track frame in its up and down movements; said guiding means including an arm depending from said frame, a

- device guiding, the lower end of said arm; said vertical guiding means also including a member having therein a pair of vertical ball grooves and a member having bearing surfaces opposed to said ball grooves; said bearing surfaces being plane, so that said balls may serve only to take the transverse thrust of the frame due to the movement of the carriage there-along.
22. In a typewriting machine, the combination with a platen carriage and a series of rearwardly striking type-bars, of a carriage-track frame movable up and down, guiding means connected to the upper portion of said carriage-track frame for preventing forward or backward movement thereof; means also connected to the lower portion of said carriage-track frame for preventing the same from swinging or tilting forwardly or backwardly, independent means for preventing the said frame from moving transversely, and means also engaging the sides of said carriage-track frame for keeping the same level while shifting up and down.
23. In a type-writing machine, the combination with a platen carriage and a series of rearwardly striking type-bars, of a carriage-track frame movable up and down, guiding means for preventing forward and backward movement of said carriage-track frame, means for preventing said frame from moving transversely, and relatively adjustable means also engaging the sides of carriage-track frame for keeping the same level at the shifting operation.
24. In a typewriting machine, the combination with a platen carriage and a series of rearwardly striking type-bars, of a carriage-track frame movable up and down; pivoted devices connected to the sides of said frame and also to the lower portion thereof for guiding the same up and down; and a spring partially balancing said frame and carriage.
25. In a front-strike writing-machine, the combination with a platen carriage and a series of rearwardly striking type-bars, of a carriage-track frame movable up and down, and guiding links connected to the upper and lower portions of said carriage-track frame and pivoted to the framework.
26. In a front-strike writing-machine, the combination with a platen carriage and a series of rearwardly striking type-bars, of a carriage-track frame movable up and down, and guiding links connected to the upper and lower portions of said carriage-track frame and pivoted to the framework; said guiding links extending forwardly from said track frame, and the latter being provided with means to prevent transverse movement thereof, including a member having vertical ball track, a ball running upon said track, and a member having plane vertical bearing surface to bear upon said ball.
27. In a front-strike writing-machine, the combination with a platen carriage and a series of rearwardly striking type-bars, of a carriage-track frame movable up and down, and means, including a link pivoted to said frame and also to the framework of the machine, for guiding said frame in its up and down movements, said guiding means including bearing balls and tracks for preventing transverse movement of said frame.
28. In a front-strike writing-machine, the combination with a platen-carriage, of a track frame for said carriage, said frame being shiftable up and down, a set of forwardly extending links pivoted to said shifting frame at different heights and pivoted at their forward ends to the framework of the machine, and independent means for preventing sidewise movement of the shifting frame.
29. In a front-strike writing-machine, the combination with a platen carriage, of a frame shiftable up and down and supporting said carriage, a pair of horizontal links pivoted to said frame and also to the framework of the machine, a third link also pivoted to said shiftable frame at a different height from said pair of links, said third link being pivoted to the framework, and means, including a set of balls and a track therefor, to prevent lateral play of said frame, while permitting the latter to be guided by said links.
30. In a front-strike writing-machine, the combination with a platen carriage, of a carriage-track frame shiftable up and down, means for guiding said frame in its up and down movements, so that it cannot move forwardly or backwardly, said guiding means including a key-controlled rocking frame movable up and down, and a pair of supports extending from the sides of said rocking frame to the sides of said carriage-track frame.
31. In a front-strike writing-machine, the combination with a platen carriage, of a carriage-track frame shiftable up and down, means for guiding said frame, said guiding means including a rocking frame movable up and down, and a pair of independently adjustable supports extending from the sides of said rocking frame to the sides of said carriage-track frame.
32. In a type-writing machine having a base, the combination with a platen carriage and a series of rearwardly striking type-bars, of a carriage-track frame, links pivoted to the sides of said frame and extending forwardly to the front of the machine and pivoted to the framework at their forward ends; means, including a set of bearing balls, for guiding said track frame in its up and down movements, so as to prevent lateral movement thereof, a frame lying in the base of the machine and pivoted thereto so as to rock

up and down, said frame being pivoted at its rear end to said carriage-track frame, a key for operating said pivoted frame, and independently adjustable supports between the sides of said pivoted frame and sides of said carriage-track frame.

In testimony whereof I have signed my

name to this specification in the presence of two subscribing witnesses.

CHARLES W. HOWELL.
